APPARATUS FOR MAKING FLOUR

Elijah M. Kinslow, Barstow, Calif., assignor, by
mesne assignments, to Vitamin Milling Corporation,
Los Angeles, Calif., a corporation of
Delaware

Application September 12, 1930, Serial No. 481,519
Renewed February 10, 1934

8 Claims. (Cl. 83—42)

It has been found in practice, in comminuting grain in a buhr mill, that the heat generated between the stones has a deleterious effect upon the constituents of the grain, resulting in a flour product which is vitally lacking in nutritive value. The action of this frictional heat upon the chemicals, such as phosphorous, potash, lime and silicon, so alters and changes their chemical properties as to destroy their otherwise beneficent effect as food products. It is therefore the foremost object of the present invention to provide apparatus whereby the mill and flour products are air-cooled and kept cool during the grinding operation, to preserve, as far as possible, all of the chemical properties of the grain in their natural state. It is furthermore an object—in addition to air-cooling the mills and products—to carry off excessive moisture from the resulting flour products, and to do this in such a way that a minimum amount of flour is lost in the process.

The subject matter of this application was divided out of my application, filed April 18th, 1922, serially numbered 554,897, entitled "Method of and apparatus for making flour," which issued as United States Letters Patent No. 1,728,184, on September 17th, 1929.

The present invention, as herein disclosed in its preferred specific embodiment, deals with the apparatus for the milling of flour wherein all of the constituents of the grain are utilized; although in principle, it need not be limited to such. In the apparatus, herein shown and described, I use two mills, one in which the whole grain is first ground, and one in which the tailings from the bolter are reground, after which they are mixed with the products of the first mill so that, except between the bolter and the second mill wherein the unbolted integuments are handled, the whole comminuted products of the grain pass through the apparatus in a commingled state. The nutritive value of a flour product of the whole grain is well known and need not be here further enlarged upon.

The essential details of my apparatus will be more fully disclosed in the following specification, reference being had to the accompanying drawing for illustrative purposes, in which drawing—

Fig. 1 is a diagrammatic layout, in sectional elevation, of an apparatus suitable for carrying out the steps of my process; and

Fig. 2 is a fragmentary sectional view through one of the mills illustrating its preferred arrangement.

In the drawing I have illustrated apparatus

embodying the essential elements for suitably carrying out the several steps of my process, but it is to be understood that such apparatus need not necessarily be limited to the precise arrangement shown and to be hereinafter described. 60

The apparatus comprises essentially two buhr mills, designated by the letters A and B, mounted side by side; having discharge chutes 10 and 11, respectively, discharging into a blower 12. The blower 12 discharges into the lower end of one 65 side of an elevator 14 just above the boot, the latter designated by the numeral 13; and this elevator discharges as its upper end into a chute 15, which communicates with the upper or receiving end of a bolt 16. The bolt 16 is contained 70 within a bolt housing 17; and the fines passing through the bolt are deposited in a trough 18, in the bottom of the housing 17, and are thence conducted to suitable storage bins (not shown) through the medium of a screw conveyor 19 operating 75 in and through a discharge chute 20. The integuments or coarser particles failing to pass through the bolt 16 are discharged from its lower end into a suitable hopper 21, mounted on the upper end of a tube 22; the latter connecting at 80 its discharge end with the mill B.

The air blast produced by the blower 12 is dissipated by discharging through the side 14a of the elevator 14 and chute 15, into the bolt casing 17, or through a suitable tube 23, connected at 85 its lower end to the opposite side 14a of the elevator 14 and at its upper end to a suitable separator 24 mounted upon the bolt housing 17. The separator 24 also has an inlet tube 25 communicating with the bolt housing 17, at a point adjacent the discharge end of the bolt 16, and a return chute 26 situated above the bolt 16, and discharging 90 on top of it or beside it intermediate its ends.

The buhr mills A and B, are preferably identical and may be of any approved size and design suitable for properly accomplishing the comminution of the grain, such as overrunner or underrunner stones, or of the roller type. For illustrative purposes I show (in Fig. 2) a typical one of such mills, of the overrunner type, comprising a pair 95 of buhr stones 27 and 28; the former being stationary and supported upon a suitable framework 29; while the latter is rotatable on top of the stone 27, and may be driven by any suitable power through the medium of shafts 30 and 31. 100 A hood 32 is preferably removably mounted over the upper stone 28; having an upper conical portion 33, terminating in a tube 34. The body portion of the hood 32 is slightly larger in diameter than the stone 28; and the annular space sur- 110

rounding the stone within this hood may be closed at its bottom by a suitable annular plate 35 surrounding the stone 27 and positioned just below the grinding faces, as shown in Fig. 2.

- 5 The discharge chutes 10 and 11 are secured at their upper ends in apertures in the plates 35 intermediate the stones and the hood so as to form a comparatively air-tight joint. It may be also noted here that the hoods 32 are substantially 80 air-tight, and form substantially air-tight coverings for the stones, except for the openings into the chutes 10 and 11 and tubes 34. Hoppers 36 are carried by the stones 28, having reduced lower ends 37 extending into the eyes 38 of the stones; their upper ends being of a size to almost but not quite extend to a juncture with the upper conical portions 33 of the hoods 32. Feed pipes 22 and 39 extend through the conical tops of the hoods 32 and terminate just above the hoppers 36 to discharge grain and comminuted particles therein, as will be more fully hereinafter explained.

The upper ends of tubes 34 are preferably connected by a common tube 34a leading away from the mills A and B and preferably to the exterior 25 of the building in which they are housed in order that fresh cool air may be supplied to the mills.

The discharge chutes 10 and 11 make air-tight connections at their lower ends with the housing of the blower 12; and the blower may be operated in any suitable manner to draw cool air through tubes 34a and 34, into the hoods 32 and down through the discharge chutes 10 and 11, discharging it into the bottom of the elevator 14. In thus drawing fresh air—preferably from the exterior 30 of the building—into the hoods 32, the bulk of it will be drawn down into the hoppers 36 (which are preferably situated directly beneath and concentric with the tubes 34) through the eyes 38 of the stones and out radially between their contiguous grinding surfaces, and thence downwardly through the chutes 10 and 11, and into the elevator 40 14. Additionally, a proportion of the air drawn into the hoods 32, through the tubes 34, will pass downwardly therein around the tops of the hoppers 36 to cool the perimeters of the stones 45 28 and then likewise pass outwardly through the chutes 10 and 11. The division of the air blast into two streams is encouraged by the hopper 36 being spaced close to the walls of hood 33. In 50 effect, therefore, the hopper serves as a partition associated in function with air inlet 34 and blower 12.

After cool air has been thus drawn through the mills A and B and exhausted into the elevator 55 14, it has served its purpose in cooling the mill and the grain being ground, except possibly for its secondary function of carrying off any moisture that may be in the flour product as it is delivered to the elevator 14. After being discharged into the elevator 14 it is necessary to dissipate the force of the blast produced by the blower, and this I do by permitting it to discharge up the housing 14a of the elevator 14, past the endless bucket elevator 14b—and for this purpose the housings 60 14a are made sufficiently large to admit of the air passage without interfering with its conveyance of the ground products from the bottom thereof, or it may be discharged up the tube 23 and into the separator 24, or through both of them. The air blast directed up the elevator 65 housings 14a will discharge into the tube 15, connecting with the bolt housing 17, and into the receiving end of the bolt 16. It will thence pass longitudinally through the bolt 16 and impinge 70 75 against the opposite end 17a of the housing 17,

whence it will be deflected up the tube 25 and into the separator 24, where the flour products will be separated in the usual manner and settle back into the bolt housing 17 through the tube 26 and be deposited on top of the bolt 16 intermediate its ends; while the air blast will be exhausted through the tube 40. In discharging up the tube 23 the blast will travel directly into the separator 24, the air current passing out through the tube 40, and the separated flour products returning to the bolt housing 17 through the tube 26, as just described.

The separator 24 may be of any of the approved forms—preferably of the “cyclone” type—it being only essential to my process that it be mounted upon the bolt housing 17 in the manner shown, so the separated flour products will be redeposited in the housing on top of the bolt 16, or intermediate its ends, and thence in the trough 18 at its bottom and conveyed to the storage bins, as hereinbefore described. In cases where I utilize the elevator housing 14a as an exhaust passage for the air blast from the blower 12, I prefer to make the arrangement as illustrated so that the air blast will be carried through the bolt and impinged against the rear wall 17a and thence into the separator, while the return passage from the separator deposits the separated flour products in the housing 17 intermediate the ends of the bolt. In this way the air currents passing through 105 the bolt and into the separator will not interfere with the return of the separated flour products into the bolt housing through the tube 26.

In operation the grain is first fed to the mill A through the feed tube 39 from whence it passes, 110 and is also drawn, through the chute 10, to the blower 12 and is exhausted into the elevator 14 above the boot 13. The elevator travels in the direction indicated by the arrows and carries the flour products from the mill A upwardly and 115 deposits them in the tube 15, which conveys them into the receiving end of the bolt 16. A short screw conveyor 16a on the end of the bolt shaft 16b discharges the flour products from the lower end of the tube 15 into the receiving end of the 120 bolt as indicated by the arrow. The fines passing through the bolts 16 are deposited in the trough 18 in the bottom of the housing 17, and are carried away by the screw conveyor 19 operating in the tube 20, to suitable storage bins. The 125 coarser particles or tailings failing to pass through the bolt 16 are discharged from its lower end into the hopper 21, thence pass through the tube 22, to the mill B, where they are reground and discharged through the chute 11 to the blower 12, 130 from whence they are carried in a commingled state with the products of mill A, through the mill as hereinbefore described. Thus the first ground products and the tailings from the bolt are always passing through the apparatus in a 135 thoroughly commingled state, except when the tailings are traveling from the discharge end of the bolt through the tube 22 to the mill B, and thence to the blower 12. This method of grinding results in a flour product of the whole grain, 140 thoroughly ground and chemically uninjured by the action of heat.

During the aforementioned steps the blower 12 is drawing cool air through the mills A and B, and exhausting it into the elevator 14. From 145 this point the air blast is dissipated up the elevator 14 or through the tube 23, or through both of them. In the case of the former it passes through the tube 15; through the bolt 16, and up the tube 25; into the separator 24, where the 150

flour particles are separated and return to the bolt housing 17 through the tube 26, while the air passes out through the exhaust tube 40. In the case of the latter the air blast is dissipated directly up the tube 23 to the separator 24, where the flour is separated and returned to the bolt housing, as described.

While I have herein shown and described the preferred specific apparatus for carrying out the several steps of my process, it is nevertheless to be understood that I do not wish to be limited by the particular apparatus and arrangement shown and described, but that I desire to make any such changes or modifications in arrangement as will properly come within the scope of the appended claims. For instance, I may dispense with the use of the tube 23, connecting the elevator 14 and separator 24, and utilize only the elevator housings 14a through which to exhaust and dissipate the blast from the blower 12, or I may use only the tube 23 for this purpose. The essential object to be accomplished in this connection is to so handle the blast from the blower, after it has accomplished its initial function of cooling the mills, as to exhaust it from the apparatus without its carrying with it any quantity of flour.

Having described my invention, I claim:

1. A milling apparatus comprising a mill having upper and nether stones; a material inlet to the mill; an air inlet to the mill; a second mill having upper and nether stones; an air inlet to the second mill; a blower; a discharge chute connecting the first mill and the blower; a discharge chute connecting the second mill and the blower, said air inlets, discharge chutes and blower being arranged to draw cool air through the upper stone and out radially between the grinding surfaces of the upper and nether stones of each mill; a bolt adapted to separate fine particles from tailings; an elevator connecting the discharge end of the blower with the bolt; a housing for the elevator, said housing being adapted to convey air from the blower to the bolt; a tailings discharge connection leading from the bolt to the second mill; a separator; a discharge connection between the blower and the separator; and a discharge connection between the separator and the bolt.

2. A milling apparatus comprising a mill having upper and nether stones; a material inlet to the mill; an air inlet to the mill; a second mill having upper and nether stones; an air inlet to the second mill; a blower; a discharge chute connecting the first mill and the blower; a discharge chute connecting the second mill and the blower; said air inlets, discharge chutes and blower being arranged to draw cool air through the upper stone and out radially between the grinding surfaces of the upper and nether stones of each mill; a bolt adapted to separate fine particles from tailings; a bolt housing; an elevator connecting the discharge end of the blower with the bolt; a housing for the elevator, said housing being adapted to convey air from the blower to the bolt; a tailings discharge connection leading from the bolt to the second mill; a separator; a discharge connection between the blower and the separator; and a discharge connection between the separator and the bolt housing.

3. A mill comprising, in combination: an upper stone having an eye therethrough; a nether stone; the two stones having opposed grinding faces; a substantially air-tight jacket encasing

the two stones; a hopper associated with the upper stone forming a passage substantially continuous with the upper end of said eye, the rim of said hopper and the interior wall of said jacket being separated by a relatively narrow clearance; an air inlet in the jacket above the hopper; a materials inlet in the jacket above the hopper; a discharge outlet in the jacket below the hopper; and means to draw a stream of air in through the inlet port and out through the outlet port, said hopper being adapted to divide said stream of air into one stream passing around the rim of the hopper and the periphery of the upper stone and one stream passing through said hopper and through said eye of the upper stone and radially outward between said opposed grinding faces of the two stones.

4. A mill comprising, in combination: an upper stone having an eye therethrough; a nether stone; the two stones having opposed grinding faces; a substantially air-tight jacket having side walls circular in plan encasing the two stones; a round hopper associated with the upper stone forming a passage substantially continuous with the upper end of said eye, the rim of said hopper and the interior wall of said jacket being separated by a relatively narrow annular space; an air inlet in the jacket above the hopper positioned to direct a stream of air both through the hopper and through said annular space; a materials inlet in the jacket above the hopper; a discharge outlet in the jacket below the hopper positioned to unite the divided air stream; and means to draw a stream of air in through the inlet port and out through the outlet port.

5. A mill comprising, in combination: an upper stone having an eye therethrough; a nether stone; the two stones having opposed grinding faces, a substantially air-tight jacket, having a cone-shaped upper portion, encasing the two stones; a conical hopper associated with the upper stone forming a passage substantially continuous with the upper end of said eye, the rim of said hopper and the interior wall of said conical portion of the jacket being separated by a relatively narrow annular space; an air inlet in the jacket above the hopper positioned to force air both through and around the hopper; a materials inlet in the jacket above the hopper; a discharge outlet in the jacket below the hopper; and means to draw a stream of air in through the inlet port and out through the outlet port.

6. A mill comprising, in combination: a revolvable upper stone having an eye therethrough; a nether stone; the two stones having opposed grinding faces; a substantially air-tight jacket having side walls circular in plan encasing the two stones; a conical hopper mounted on the upper stone to revolve therewith and forming a passage substantially continuous with the upper end of said eye, the rim of said hopper and the interior wall of said jacket being separated by a relatively narrow annular space; an air inlet in the jacket above the hopper positioned to direct air both through and around the hopper and upper stone; a materials inlet in the jacket above the hopper; a discharge outlet in the jacket below the hopper; and means to draw a stream of air in through the inlet port and out through the outlet port.

7. A mill comprising, in combination: a revolvable upper stone having an eye therethrough; a nether stone; the two stones having opposed grinding faces; a substantially air-tight jacket, having a cone-shaped upper portion, encasing

the two stones; a conical hopper mounted on the upper stone to revolve therewith and forming a passage substantially continuous with the upper end of said eye, the rim of said hopper and the interior wall of said conical portion of the jacket being separated by a relatively narrow annular space; an air inlet in the jacket above the hopper positioned to direct air both through and around the hopper and upper stone; a materials inlet in the jacket above the hopper; a discharge outlet in the jacket below the hopper; and means to draw a stream of air in through the inlet port and out through the outlet port.

8. A milling apparatus comprising: a mill having upper and nether stones; a substantially airtight jacket encasing the two stones; a material inlet in the jacket above the upper stone; an air inlet in the jacket above the upper stone; a discharge chute extending from the jacket; a blower associated with the discharge chute to draw a stream of air through the mill; and a hopper substantially continuous with the eye of the upper stone forming an air passage to direct air through the eye and out radially between the grinding surfaces of the two stones, said hopper defining, with the jacket, a second air passage directed to the perimeter of the upper stone and restricted to offer sufficient resistance to the air stream to substantially balance the resistance to the air stream offered by the grinding surfaces.
